UNITED STATES PATENT OFFICE.

CARL J. SCHULTZ, OF CLEVELAND, OHIO, ASSIGNOR TO THE NATIONAL MALLEABLE CASTINGS COMPANY, OF CLEVELAND, OHIO, A CORPORATION OF OHIO.

UNCOUPLING-ROD BRACKET.

1,000,299.

Specification of Letters Patent. Patented Aug. 8, 1911.

Application filed June 30, 1910. Serial No. 569,837.

To all whom it may concern:

Be it known that I, CARL J. SCHULTZ, a resident of Cleveland, Cuyahoga county, Ohio, have invented a new and useful Uncoupling-Rod Bracket, of which the following is a full, clear, and exact description, reference being had to the accompanying drawings, forming part of this specification, in which—

10 Figure 1 is a side elevation partly in section showing one form of bracket constructed in accordance with my invention. Fig. 2 is a front elevation of the same. Fig. 3 is a top plan view. Fig. 4 is a side elevation showing another form of the base plate, and Fig. 5 is a plan view of the same.

15 My invention relates to uncoupling rod brackets and is designed to provide a simple, cheap and efficient bracket having a detachable holding member which may be laterally engaged with the uncoupling rod at any point in its length without endwise threading. The holding member may also be detached from the rod by sidewise movement.

20 In the drawing, referring to the form of Figs. 1, 2 and 3, 2 represents a base plate which in this form is adapted to be secured to the vertical face of an end sill or dead block and hence takes the form of a shelf or bracket structure. In this form the casting has a vertical plate portion 3 provided with bossed holes for receiving bolts or rivets to secure it to the car and is preferably provided with a strengthening web 4 connecting the base plate and the vertical plate portion. This base plate may of course vary in form and may be made of either casting or forging, or, in any other desirable way. From the upper surface of the base plate 2, preferably integral therewith, a lug 5 projects upwardly, this lug being cylindrical in the form shown. The detachable rod carrying or supporting member 6 is U-shaped in form, the legs of the U having registering holes by which it is slipped down over the upwardly projecting lug or pin on the base plate. When thus placed in position, it is secured by a cotter pin 7 projecting through a transverse hole 8 in the upper end portion of the lug or pin. The cotter locks the rod carrying member in place and prevents its accidental removal. I have also shown the rod carrying member 55 as having a downwardly bending lip exten-

sion 9, which fits against the forward end of the base plate and is designed to prevent sidewise swinging movement of the holding member which might cause it to bind on the uncoupling rod. The uncoupling rod passes 60 through the opening marked 10 and is retained in position so long as the rod holding member is retained by the cotter on the through pin or lug.

65 In the modification of Figs. 4 and 5, I show a form similar to that of Figs. 1, 2 and 3, except that the base plate 2a is a simple plain plate designed to be secured on the top of the end sill or other horizontal surface of the car and having suitable securing lugs 70 or projections. In these figures, parts similar to those of Figs. 1, 2 and 3 are marked with similar numerals with the letter 'a' applied.

75 The advantages of my invention will be obvious to those skilled in the art. A simple and economical form of uncoupling rod bracket is provided having only three parts. The rod carrying member may be placed on the uncoupling rod at any point of its length without threading it along the rod at either end. This rod may be easily secured in place or detached.

70 Many variations may be made in the form and arrangement of the parts within the 85 scope of my invention as defined in the claims.

I claim:

1. An uncoupling rod bracket having a support, a U-shaped rod carrying member 90 detachably secured to said support and a closing member engaging the legs of the U-shaped rod carrying member; substantially as described.

2. In an uncoupling rod bracket, a support having a projection, and a U-shaped rod carrier having its U-forming arms engaging said projection; substantially as described.

3. In an uncoupling rod bracket, a base plate having an upwardly projecting pin with a hole in its upper portion, and a U-shaped rod carrier having holes arranged to receive the pin and being secured by a cotter through the hole in the pin; substantially 105 as described.

4. In an uncoupling rod bracket, a base plate having a projecting pin, and a U-shaped rod carrier secured on the pin and having a lip engaging the base plate to 110.

avoid side swinging of the carrier; substantially as described.

5. In an uncoupling rod bracket, a support, a rod carrier secured on said support and having an open side, and a closure for the open side projecting from the base plate; substantially as described.

6. In an uncoupling rod bracket, a support having a projecting closing member,

and a rod carrier having an open side secured and closed by said closing member; substantially as described.

In testimony whereof, I have hereunto set my hand.

CARL J. SCHULTZ.
